CLOTHES DRYER CONDENSING SYSTEM
Stephen L. McMillan, Wheaton, Ill., assignor to General
Electric Company, a corporation of New York
Filed Mar. 13, 1961, Ser. No. 95,107
4 Claims. (Cl. 34—54)

The present invention relates to clothes dryers which include a closed cycle condensing system and more particularly to an improved construction and control of the condensing system.

It is therefore an object of the invention to provide an improved and simplified condenser construction and control system for a clothes dryer.

It is a further object of the invention to provide in a closed cycle condenser dryer system, a dual purpose high temperature thermostat which responds either to malfunctioning of the heaters or to an overflow of liquid in its condenser chamber.

It is a further object to provide a simplified shut-off mechanism for a dryer, which responds to an overfill of liquid in the condensing chamber of a clothes dryer to stop the dryer operation.

It is known that in a condensing clothes dryer, a heated air flow is used to evaporate moisture from the clothing, and subsequently the moisture is condensed from the air by means of cool water which is introduced into contact with the heated air within the dryer cabinet. The resultant liquid is discharged to drain either by gravity or by a pump. It will be apparent that should the outlet drain or the pump become clogged, the continued flow of condensing water could flood the clothes dryer with obvious undesirable results.

To alleviate this difficulty in a water condenser clothes dryer or the like, the present invention contemplates a liquid control means wherein a control circuit is provided in combination with circuit interrupting means responsive to a predetermined liquid level in the casing or container for the liquid, whereby the operating circuit for the dryer is rendered inoperative should the liquid in the casing or container reach a predetermined level because of clogging of the discharge opening therefor, or failure of the pump, if such be used in the apparatus.

The circuit interrupting means utilized as the preferred control herein is the thermostat common to clothes dryers as the high temperature thermostat required by most safety codes to interrupt at least the power to the heating element in the circumstance of unduly high temperatures. The thermostat in addition to its normal use controls the maximum condenser water level in that the air which is circulated over the heaters to extract heat therefrom and maintain them at a safe operating temperature is channeled through the condensing chamber. The chamber is so constructed that an excessive quantity of liquid in the condensing chamber will shut off the air flow; consequently the heaters will overheat and the thermostat will operate to open the power circuit.

To be more specific about the construction of the condenser chamber, the condensing chamber includes one or more baffles forcing the air flow into a serpentine path. The main baffle depends from the chamber ceiling to a predetermined height. When the level of water within the chamber reaches this height, an effective barrier to the flow of air is formed by the combination of baffle and water below it. This barrier will tend to block or interrupt the flow of air to the heaters, whereupon the heaters will, as mentioned, overheat and trip the high temperature thermostat. In the preferred circuit combination, the tripping of the thermostat will open the circuits to the dryer drive motor, the timer motor, the air heaters and the water inlet control and as a result the dryer will be

2

deenergized pending a manual resetting of dryer control mechanism.

It should be noted that the machine operator may reset the dryer without correcting the fault and operation will be resumed until the thermostat heats sufficiently to re-open the operative circuits. Persistence in restarting would conceivably cause the machine to overflow; however, the shut-off level in the condenser chamber may be so related to the capacity of the chamber that shut-off will occur at but a fraction of the capacity of the condensing chamber. It is a further feature of the invention that the condensing chamber is constructed to allow ready access to its interior for the purpose of freeing the drain by removal of the obstructing material or object.

The invention both as to its organization and principle of operation, together with further objects and advantages thereof, will best be understood by reference to the following specification taken in connection with the accompanying drawings in which:

FIG. 1 is a front perspective view of a clothes dryer utilizing my invention with the outer walls shown in outline and portions broken away;

FIG. 2 is a sectional side view of the dryer viewed along the line 2—2 of FIG. 1;

FIG. 3 is a side view in cross section of the condensing chamber;

FIG. 4 is a schematic wiring diagram of the control circuit incorporated in the dryer of FIGS. 1 and 2; and

FIG. 5 is a partial side view as FIG. 2 showing the lower right corner of the dryer with the trouble access door removed.

Referring now in detail to the dryer 10 of FIGS. 1 and 2, the dryer there shown is of the type known as "Axial-Flow." In dryers of this type there is an imperforate walled cylindrical drum 12, journaled to rotate on a horizontal axis within a substantially imperforate appearance cabinet 14. The drum includes a plurality of perforations 16 about its rear wall 18 and a central access opening 20 in its front wall 22. Adjacent and outwardly of the opening 20, the cabinet 14 is ported with a cabinet access opening 24 which is normally covered by a side hinged door 26. Door 26 is pivotal between a closed position denying access to the drum interior and an open position allowing free entry to the drum interior to allow loading of the drum.

The dryer shown, further is of the recirculatory type in which a flow of air is heated, passed through the drum under suction pressure from a blower, and passed through a treating chamber for return flow through the system. Within this generally described system there are positioned a plurality of radiant heaters 30 which are secured to an annular stationary plate 32 concentric to and outwardly spaced from the rear drum wall. These heaters will heat air in circulation just prior to entry into the drum via the inlet perforations 16 in the drum rear wall. To exhaust air from the drum there is provided adjacent the drum front opening a downwardly directed duct 34 which serves to channel exhausted air to the rotary blower 36. Air is emitted radially from the blower to a horizontal duct 38 which leads into one end of the essentially rectangular condensing chamber 40. At the opposite end of the condensing chamber, there is an exit air duct 42 which is upwardly positioned to direct the exit air from the condensing chamber past the heaters for recirculation to the drum.

For driving the motive mechanisms within the dryer there is provided a main drive motor 50 mounted to the cabinet base structure (not shown) and which by obvious and generally known mechanical expedients such as pulleys and the like rotates blower 36, drum 12 and also

a condenser drain pump (shown only representatively designated as 64). The motor is a conventional fractional horsepower appliance motor with one end of its coaxial shaft extending therefrom for driving the blower rotor and the opposite end of the shaft extending from the motor to drive the drain pump and drum by suitable belt and pulley connections.

Further describing the recirculatory air flow path, it can be seen that air leaving chamber 40 flows into duct 42 and then upwardly into the annular space 52 between stationary back plate 32 and the drum rear wall 18. This space 52 most aptly may be called the heating area since within the area are positioned the previously mentioned resistance heaters 30. These heaters are connected to a source of 230 volt alternating current, as will be described more fully later, and heat the air prior to entry into the drum through perforations 16. Within the drum the wet clothes which are to be dried are tumbled in a rotary manner. Heated air is passed over the clothes and tends to absorb moisture from the clothes. The highly humid air which results from this absorption passes through the drum front access opening 20, and since the front door seals the cabinet, little or no air escapes to the surrounding room. The drum access opening is sealed about most of its periphery and is only open along its lower segment, whereupon the air is allowed freedom to flow only through grille 54 which covers the open segment of the access opening into vertical duct 34. This duct is generally rectangular in cross section and may contain a suitable mesh screen 56 depending from grille 54 and substantially traversing the cross sectional area of the duct 34. This screen serves as a primary means to stop and collect lint which may be air-borne by the moisture bearing air being exhausted from the drum.

From duct 34 the air is sucked into the blower and expelled radially into the duct 38 leading to chamber 40 for flow generally along the pattern indicated by the arrows 58 in FIGS. 2 and 6. This condenser chamber is essentially liquid retentive in character and has a lower wall or floor 60 tapering to a drain opening at its lowest point. This drain opening leads to drain pipe 62 which has connected thereto a suitable drain pump 64 of known design driven by motor 50.

Further, the condensing chamber has along its upper surface a plurality of spaced, directed nozzles 66 which emit a fine spray of water over a large volume of the chamber to thereby provide a large area of contact between the cool spray mist and the heated moist air passing horizontally through the chamber. The nozzles are controlled by a suitable electrically operated solenoid 68 and are fed by a cool water inlet pipe 70. Positioned downstream of the spray nozzles within the chamber is an impermeable baffle or water wall 72 which depends from the top surface into the chamber and terminates a predetermined distance above the floor 60 of the chamber. The baffle in its preferred form extends completely across the chamber 40 to deflect the air passing through the chamber downwardly to force the air into the serpentine path shown by the directional arrows 58. This baffle further is wetted by spray from the adjacent nozzle and serves as a wetted surface which will provide further condensing area for the warm exhaust air. By this means, additional moisture will be condensed from exhaust air. The dehumidified air will flow upwardly through the opening 74 high on the downstream wall of the chamber for recirculation through the heating area and drum. The condensed water will be carried away by the drainage system. The drying cycle continues in this manner until terminated by the expiration of the drying period allotted.

For the purpose of selectively establishing the duration of the operative cycle, there is provided a time cycle controller 76 including a manually rotatable knob 78 which extends outwardly of the backsplasher 79 to be readily accessible to the operator. The control knob may

be of the type which may be depressed axially to momentarily close a start switch. When rotated through an arc, the knob as pre-set will determine the cycle duration in its timed return to normal. This facet of the dryer operation is well known in the art, and in the detail necessary for an understanding of the invention, may be examined with reference to the circuit of FIG. 4. The circuit of FIG. 4 is shown terminating in three conductors L1, L2 and N which are the generally known conductor designations for connection to a three wire Edison 236 volt, single phase alternating current source. As generally known, connection to leads L1 and L2 supplies 236 volts while connection to L1 and N or L2 and N serve to supply 118 volts. In the FIG. 4 circuit there is shown the windings of drive motor 50 which include start winding 80 and run winding 82. The drive motor further includes a centrifugal switch 84 designed to open when the motor reaches a predetermined speed thereby opening the circuit to the start winding. There is further included as a form of heater control switch, motor actuated switch contacts 86 which only close when the drive motor has reached its running speed. These contacts 86 open when the speed of the motor falls below a predetermined minimum and will as a result open the circuit to the resistance heating elements 30.

Further in the circuit to the heaters 30, there is provided a cycling thermostat 90, which is designed to cycle the heaters to maintain a heated air at a predetermined low level. This thermostat is physically positioned in the blower exhaust duct 38 (see FIG. 1) to sense the exhaust air temperature and maintain this temperature at a low operating level in generally known fashion. The heater circuit also includes timer controlled switch contacts 92 which close when the timer knob has been rotated off-normal. The heater operating circuit may be traced from lead L1 through motor controlled contacts 86, thermostat 90, both heating elements 30 connected in parallel, timer contacts 92 and then back to lead L2. In this way heaters 30 are connected to the 236 volt source conductors when the following conditions are in effect: motor 30 is operating at its running speed maintaining contacts 86 closed, thermostat 90 is closed indicating low temperature, and knob 78 has been rotated off-normal maintaining switch contacts 92 closed. It should be noted that all these contacts are in series with the heaters so that opening of any one will open the circuit to the heating elements.

The remainder of the circuit is connected to 118 volts across conductors L2 and N. In this 118 volt circuit connected in parallel are the drive motor windings 80 and 82, water inlet solenoid 68 and timer motor 94. This timer motor is of the conventional type used in appliance timing and includes a motor which through a suitable transmission (not shown) drives an output cam shaft in step-by-step fashion through an arc of determinate length each fixed interval of time. The duration of the cycle is determined by the amount of arc through which manual control knob 78 is rotated and the time necessary for the timer motor to return to normal at its fixed speed. Contacts controlled by the timer motor include contacts 92 in the heater circuit, contacts 96 in the operating circuit drive motor 50 and contacts 97 leading to the solenoid. In the circuit shown, which has been reduced to the essentials of the present invention, contacts 96 are closed on rotation of control knob 78 and these contacts will open at the conclusion of the proper timed period; timer motor 94 having turned its cam shaft (not shown) back through the arc set at the control knob. The circuit to the parallel drive motor circuit further includes door switch contacts 98 and momentary contacts 102. Door switch contacts, as the name implies, react to opening of the door to open the circuit and remain closed on closure of the door. Momentarily actuated contacts 102 are closed for a short period of time on axial depression of control knob 78 and thereby these contacts

form a starting circuit which restores on release of manual pressure and must be reset for further operation once the circuit has restored. In series with timer switch contacts 96 and door switch 98 is the high limit thermostat 104 which nominally may be called the safety thermostat. This thermostat remains closed at all temperatures below a high, safe temperature such as 260° F. This thermostat prevents excessive overheating of the machine and will open the operative circuits to the machine in any situation productive of this excessive temperature. Such a thermostat will normally be set to re-open at a lower temperature such as 220° F. The physical positioning of thermostat 104 may be seen in FIG. 2 mounted to the flange of an annular stationary plate 32 in the area above heaters 30. The thermostat will sense the temperature of air at the heaters and will rapidly respond to changes in air temperature within its critical range.

Solenoid 68 is, as mentioned, connected in parallel with timer motor and drive motor; however, this solenoid circuit is controlled by solenoid control contacts 97 which are operated by the timer shortly after the heater contacts have been closed. The delay allows the circulating air to be heated partially prior to the inception of water spray to the condensing chamber and its attendant cooling action. Further, it should be noted that timer controlled contacts 92 are closed on the start of the drying operation and will open concurrently with the opening of contacts 97 shortly before the cycle termination to allow a final, non-heated, non-condensing cool-down period. During this cool-down period, the timer controlled contacts remain closed allowing the drum to tumble for the remainder of the pre-set time.

The operation of the invention is as follows: The wet clothes to be dried are placed in drum 12, and door 26 is closed, closing door switch contacts 98. Knob 78 is rotated to the position indicating the cycle duration required. This rotation of the knob closes contacts 92 and 96. Knob 78 is then depressed closing momentary contacts 102. Closure of the momentary switch completes a 118 volt circuit to the drive motor and to the timer motor. These motor starting circuits may be traced from lead N through the parallel paths including in the first path start winding 80 and motor contacts 84, and in the second path run winding 82 of the drive motor and through the third parallel path including the winding of timer motor 94, through the multiple connection to momentary contacts 102, door switch contacts 98, thermostat 104 and closed contacts 96 to lead L2. Drive motor 50 accelerates and trips its centrifugal switch contacts 84, which opens the circuit to the start winding 80 and locks the run winding 82 over a hold path bypassing momentary contacts 102. Momentary contacts 102 then restore. The timer motor 94 and run winding 82 of the drive motor are then locked operated. As motor 50 is accelerated, contacts 86 also close completing the circuit to the heaters through closed thermostat 90 and timer contacts 92. The heaters heat the circulating air as the drum rotates for a short period following which contacts 97 close initiating the condensing action.

As mentioned previously, air is circulated by the blower through a closed cycle including the condensing chamber, inlet duct, heating area, tumbling drum, exhaust duct and back to the blower. In this way air is heated at the heaters and is passed through the drum which is being rotated to tumble the wet clothes therein. Heated air contacts the tumbling clothes and absorbs moisture from the clothes. This wet exhaust air leaves the drum through the front access opening and enters the exhaust duct 34. The screen 56 catches lint borne in the air and allows the moist air to be conducted through blower 36. The air is then emitted through duct 38 past thermostat 90 and into the condensing chamber. There, the hot, moist exhaust air meets the spray of cooling water from nozzles 66 and the moisture condenses out. This condensate is drained out drain pipe 62 by the action of drain

5 pump 64 which, as previously described, is operated by drive motor 50.

15 The comparatively dry air then passes under baffle 72, which optimally extends for the full width of the condensing chamber 40, and out air vent 74 for recirculation past heater 30 and high temperature thermostat 104 into the drum. This cycle continues until air temperature at thermostat 90 rises above the acceptable operating limit and the thermostat opens its contacts to deenergize heater 30. The temperature drops and thermostat 90 recloses its contacts. Thermostat 90 cycles the heaters in this manner for the entire timed period. At the conclusion of the heat dry period, timer contacts 92 and 97 restore. Contacts 92 open the heater circuit, and contacts 97 restore the solenoid 68 shutting off the flow to nozzles 66. The motor continues tumbling the clothes for a cool down period after which timer 94 having completed its cycle opens contacts 98 to deenergize timer motor 94 and the drive motor run winding 82. Drive motor 50 slows down and eventually stops its rotation. Contacts 84 and 86 restore on slow down of the motor and the circuit is thereby returned to normal.

20 25 30 35 40 45 50 55 60 65 70 75

With a closed air flow system as shown, blockage of air flow due to any cause, will cause the heaters to overheat, there being no air circulated to carry off the heat generated. As a result the temperature at the heaters mounts very rapidly. On this temperature rise, thermostat 104 operates its contacts to the open position deenergizing the circuit to the motor run winding. The drive motor slows down and opens speed responsive contacts 84 and 86. The opening of these contacts shuts down the machine pending a reset of momentary start contacts 102. A blockage or interruption of air flow may also occur due to an accumulation of lint in filter screen 56 impeding the air flow. In this latter event the machine operator may readily see that the machine is not operating and that the cycle has not concluded. On inspecting the lint screen 56 and finding it full, the operator would empty the lint filter and then reset the machine.

The other most probable cause of trouble in the machine is that which may follow an accumulation of lint or other matter within the chamber 40. This may clog drain 62 and cause condensing liquid to rise within chamber 40. Previously, diaphragm switches responsive to the increase in liquid level have been used as shut-off switches. The operating environment of such switches is incompatible with uniformity and accuracy of response, for there is at most, an available water head of only four to five inches. The limited head pressure makes it necessary to employ a very sensitive diaphragm switch, and it has been the general experience that such switches lead to false indications of difficulty and unnecessary service calls. The present invention alleviates the necessity of use of a pressure diaphragm and utilizes the high temperature thermostat 104 as the water level sensor. An overfill of water in the condensing chamber will cause a water buildup at least to the lower edge of baffle 72. Such an overfill will form a barrier covering the free area below baffle 72 and will block the air flow out of the chamber. Blockage of air flow will result in an excessively high temperature condition at thermostat 104, causing opening of the thermostat contacts 104, and subsequent machine shut-off. Thus, the baffle and excessive water level combine to block air flow on a high water condition in the condensing chamber.

It should be noted that the water retentive capacity of chamber 40 is sufficiently great that following a malfunctioning, shut-off and subsequent reset, the chamber can retain the excess of water without flooding. On reset, the condenser solenoid does not operate for a finite period during which heated air is circulated and if prior to the conclusion of this period the blockage has not corrected itself, the machine will continue to overheat and shut off.

To allow service accessibility to the drain pump and

condensing chamber, a small access opening 108 has been provided in the side of the cabinet wall as shown in FIG. 5. A door (not shown) may be hinged or held by screws to cover the opening in any suitable manner allowing easy removal. On removal of the door from opening 108, the condenser chamber 40 may be approached easily. The condenser chamber contains a door 110, secured in suitable fashion to the chamber wall to seal the chamber from leaks. The lower extent of this door optimally should be above the lower level of baffle 72 to prevent water overflow on removal of door 110 in case of trouble. This condenser door 110 may be reached following removal of cabinet door and removed to allow the drain pipe 62 to be cleared of obstructions when necessary. Needless to say, both the inner and outer doors should be replaced completely prior to re-operation of the machine.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. A laundry dryer comprising an external casing having a loading opening in a wall thereof, 25
a clothes-receiving drum mounted for rotation within said casing, a front wall of said drum having an opening communicating with said loading opening and a rear wall provided with a plurality of air inlet openings, 30
structure within said casing forming a heating chamber openly facing said drum rear wall, electric resistance heating means in said chamber, 35
structure providing a duct communicating between the front end portion of said drum and said heating chamber, said duct including a horizontally extending condensing chamber having a bottom wall configurated to form a sump communicating with an outflow pipe, 40
means comprising a cold water inlet pipe and at least one spray nozzle arranged to discharge cold water into said condensing chamber, a normally closed valve in said inlet pipe, 45
a solenoid arranged on energization thereof to open said valve, a blower for enforcing air flow in a closed circuit sequentially through said heating chamber, said drum, and said condensing chamber, in a quantity sufficient to maintain air temperature in said heating chamber below a predetermined minimum, 50
a motor for driving said blower, a baffle in said condensing chamber arranged to interrupt said air circulation upon a predetermined increase in water level within said chamber, an electric circuit common to said solenoid and said motor for energizing the same, 55
means for completing said last-named circuit, and a thermostat responsive to air temperature in said heating chamber to open said circuit upon sensing a temperature above said predetermined minimum, whereby said water inlet valve will close and said motor will be deenergized.
2. A laundry dryer comprising an external casing having a loading opening in a wall thereof, 60
a clothes-receiving drum mounted for rotation within said casing, said drum having at one end an opening communicating with said loading opening and at its opposite end being provided with a plurality of air inlet openings, 65
structure within said casing forming a heating chamber openly facing said air inlet openings, electric resistance heating means in said chamber, 70
structure providing a duct communicating between the front end portion of said drum and said heating

chamber, said duct including a condensing chamber disposed wholly below said heating chamber, said condensing chamber having a bottom wall configurated to form a sump communicating with an outflow pipe,

- means comprising a cold water inlet pipe and at least one spray nozzle arranged to discharge cold water into said condensing chamber, a normally closed valve in said inlet pipe, a solenoid arranged on energization thereof to open said valve, a blower for enforcing air flow in a closed circuit sequentially through said heating chamber, said drum, and said condensing chamber, in a quantity sufficient to maintain air temperature in said heating chamber below a predetermined minimum, a motor for driving said blower, a baffle extending across said condensing chamber intermediate the inlet and outlet ends thereof, said baffle terminating above said chamber bottom wall to interrupt said air circulation upon a predetermined increase in water level within said condensing chamber, an electric circuit common to said solenoid and said motor for energizing the same, means for completing said circuit, and a thermostat disposed in said heating chamber above the heating means therein to open said last-named circuit upon sensing a temperature in said chamber above said predetermined minimum, whereby said water inlet valve will close and said motor will be deenergized.
3. A laundry dryer comprising an external casing having a loading opening in a wall thereof, 25
a clothes-receiving drum mounted for rotation within said casing, a front wall of said drum having an opening communicating with said loading opening and a rear wall provided with a plurality of air inlet openings, 30
structure within said casing forming a heating chamber openly facing said drum rear wall, electrically activated means for increasing the air temperature in said heating chamber, 35
structure providing a duct communicating between the front end portion of said drum and said heating chamber, said duct including a condensing chamber having a bottom wall configurated to form a sump communicating with an outflow pipe, 40
means comprising a cold water inlet pipe and at least one spray nozzle arranged to discharge cold water into said condensing chamber, a normally closed valve in said inlet pipe, 45
a solenoid arranged on energization thereof to open said valve, a blower for enforcing air flow in a closed circuit sequentially through said heating chamber, said drum, and said condensing chamber, in a quantity sufficient to maintain air temperature in said heating chamber below a predetermined minimum, 50
an energizing circuit for said electrically activated air heating means, a motor for driving said blower, 55
a switch in said energizing circuit, said switch being arranged for operation by said motor from a normally open to a closed circuit condition as said motor reaches a predetermined speed, 60
a baffle in said condensing chamber arranged to interrupt said air circulation upon a predetermined increase in water level within said chamber, an electric circuit common to said solenoid and said motor for energizing the same, 65
means for completing said circuit, and a thermostat responsive to air temperature in said heating chamber to open said last-named circuit upon sensing a temperature above said predetermined minimum, whereby said water inlet valve will close

and said motor will be deenergized, and the switch in said first-named energizing circuit subsequently opened as said motor comes to a halt.

4. A condensing type clothes dryer, comprising:

a cabinet, 5

a clothes-tumbling drum therein, duct means establishing a recirculating air-flow circuit in which air is drawn from said drum and returned thereto,

said air-flow duct means including a condensing chamber having air inlet and air outlet passages communicating with said drum, 10

means for enforcing air flow through said duct means, electric resistance means for adding heat to the recirculating air prior to its return to said drum, 15

means including a water spray device adapted to be connected to a cold water supply for introducing a cold water spray into the air traversing said condensing chamber,

means communicating with said chamber for removing 20

water therefrom,

imperforate baffle means extending across the interior

15

10

of said chamber upstream of the air outlet passage thereof, said baffle means terminating above the base of said chamber to provide therewith an air-flow passage only so long as said baffle is not immersed in water within said chamber,

solenoid operated valve means for controlling water flow to said spray device,

an energy circuit for said valve means,

and a thermostat in said energy circuit, said thermostat being disposed in said air flow circuit and responsive to a predetermined increase in temperature of air therein to interrupt said energy circuit.
